CLAIM

The ornamental design for a toy helicopter, substantially as shown and described.

DESCRIPTION

FIG. 1 is a side elevational view of a toy helicopter showing our new design, the side opposite being substantially a mirror image thereof;

FIG. 2 is a top plan view thereof;

FIG. 3 is a bottom plan view thereof;

FIG. 4 is a front elevational view thereof; and

FIG. 5 is a rear elevational view thereof.

FIG. 2

FIG. 2

FIG. 3

FIG. 5

FIG. 4
